UNITED STATES PATENT OFFICE

2,267,677

SAND MULLER

William Baxter, Montreal, Quebec, Canada, assignor to Crane Co., Chicago, Ill., a corporation of Illinois

Application November 24, 1939, Serial No. 305,884

2 Claims. (Cl. 83—45)

This invention relates to a foundry sand muller having especially for its function the preparation or reconditioning of molding sand. More particularly, the invention relates to a continuously operating type of sand muller as distinguished from those generally referred to as batch type mullers.

One of the more important advantages of the present invention lies in the provision of an apparatus in which one roller or ironer completely mulls or prepares a mixture of sand, clay and bond while the said mixture is making a single pass or contact thereunder.

Another object lies in the provision of an apparatus which will continuously and efficiently mull or prepare foundry sand for molding as the said sand is fed to the muller regardless of wide variations in the quantity of sand supplied to the muller for preparation.

A still further object of the invention is to provide a sand muller which utilizes a new type of mulling action, not heretofore available, for the more efficient treatment of the sand and clay particles whereby the clay is more evenly and thoroughly distributed in the sand. As herein-after described in greater detail, the increased efficiency of my mulling apparatus is derived from a novel brushing, crushing and tearing action imparted to the sand preferably by a specially constructed roller or ironer having a peripheral velocity which is not the same as the velocity of the sand being fed to the said roller by a conveyor.

It is also a further object of my invention to provide a molding sand muller which is readily adaptable to being installed in existing sand reconditioning or transporting systems and which when installed requires a relatively small amount of power for its operation.

Other objects and advantages of my present invention will become apparent upon proceeding with the following detailed description of a preferred embodiment of the muller illustrated by the accompanying drawings in which:

Fig. 1 is a side view of the complete sand preparing unit.

Fig. 2 is a plan view thereof.

Fig. 3 is a fragmentary end view showing the preferred relative positioning of the respective sand tempering belt, the mixer and the cooling belt.

Fig. 4 is a magnified fragmentary plan view showing in detail the mounting of the roller or ironer above the tempering conveyor belt.

Fig. 5 is a side view thereof.

Fig. 6 is a sectional view showing the preferred construction of the roller or ironer.

Like reference numerals refer to like parts throughout the various views of the drawings.

Referring to Fig. 1, the preferred and conven-

tional type of foundry molding sand conditioning apparatus to which I adapt my sand muller comprises a rotary screen or riddle 1 covered by an open ended bottomless housing 2 both of which are positioned immediately above a portion of an endless belt type conveyor or tempering belt 3. The said tempering belt extends horizontally from one end of the riddle and has a plurality of stationary sweepers 4 (more clearly shown in Fig. 2) superposed upon a central portion of the belt. At the extreme end of the tempering belt 1 place an independently driven roller or ironer 5 the construction of which will hereinafter be described in greater detail. Immediately below the extreme end of the tempering belt 1 place the inlet of a conventional mixer or beater 6 (more clearly shown in Fig. 3) which may comprise an enclosed rotatable worm screw or, if desired, may incorporate any other means for mixing or beating and advancing material within the mixer to the opposite side or outlet end 7 thereof. Adjacent to the outlet of the mixer 6, I prefer to provide a conveyor or cooling and transporting belt 8.

The manner of operation of the hereinabove briefly described apparatus comprises supplying the riddle or screen 1 with used and/or new molding sand by any convenient means (not shown) such as a hopper or a conveyor belt having a chute to direct the sand into the riddle. The riddle, previously described as being rotary, is mounted upon a journaled axle 9 having the bearings 11 and 12 supported by the framework 13. A pulley 14 on one end of the axle is provided with a belt drive 15 which is interconnected with a pulley 16 suitably secured upon the driveshaft 17. Sand directed into the riddle 1 is screened by the rotary motion of the riddle and falls upon the tempering belt 3.

The belt 3 encircles a pair of journaled rollers 18 and 19 and has a plurality of supporting rollers 21 which prevent undesirable sagging of the conveyor belt. The roller 18 has a belt tension adjusting bearing 22 and the roller 19 has attached to its axle 23 a pulley 24 which by means of the belt 25 is driven by the pulley 26 secured upon the driveshaft 27. The rotational drive imparted to the pulley 19 is preferably clockwise whereupon the uppermost portion of the belt 3 will travel in the direction indicated by the arrows. Thus, sand falling upon the tempering belt from the riddle moves with the belt past the sweepers 4 which thus effect an even distribution of the sand upon the belt.

Referring now to Figs. 4 and 5, the sand, after being swept to an even thickness across the width of the belt 3, approaches the independently driven roller or ironer 5 wherein lies the essence of my invention. The ironer 5 is rotatably mounted upon a pivotable framework 28 comprising

a pair of arms loosely attached to the counter-shaft 29, the latter being supported above the tempering belt by the bearing brackets 31 and the stationary framework 32. The outermost end of the pivotable framework 28 carries a scraper 33, preferably made of rubber, leather, or the like material, which extends the length of the ironer 5. A pair of adjustable stops 34 extend upwardly from the general framework 13 and abut the pivotable ironer-carrying framework 28, maintaining the latter in its lowered position so that the ironer 5 will not come in direct contact with the belt 3. It has been found desirable to make the stops 34 adjustable so as to maintain the periphery of the ironer 5 preferably about $\frac{1}{4}$ -inch above the tempering belt, although the latter distance may be varied.

The independent drive of the ironer 5 is provided for respectively by the pulley 35 upon the shaft 23, the crossed belt 36, the pulley 37 secured to the countershaft 29, the pulley 38 also secured to the countershaft 29, the belt 39 and the pulley 41, the latter being secured to the journaled shaft 42 of the ironer 5. Thus it can readily be observed that upon proper selection of the ratio between the diameters of the pulleys 35 and 37 the peripheral velocity of the ironer 5 may be adjusted to any desired speed and that the direction of rotation of the ironer will be counterclockwise. The apparatus has been found during actual operation to give satisfactory results in the mulling of sand when the lineal velocity of the tempering belt 3 is about 212 feet per minute and the peripheral velocity of the ironer 5 is about 230 feet per minute.

In operation, the sand upon the tempering belt after being swept to an even thickness by the sweepers 4 is fed under the ironer 5 the lower surface of which, by reason of its counterclockwise movement, is traveling in the same direction as the sand but preferably at a greater velocity than the sand, whereupon the sand receives a novel brushing, crushing and tearing action which separates and intermingles the various particles constituting the sand mixture. Resilience in the action of the ironer is provided for by the tempering belt 3 which has no support directly beneath the ironer and by the pivotability of the framework 28 which allows the ironer to rise upon the occurrence of an increase in the thickness and quantity of sand upon the tempering belt. Obviously, the free riding weight of the ironer and its framework thus assist materially in the mulling treatment of the sand.

The construction of the roller or ironer 5, reference being had to Fig. 6, comprises preferably a hollow metallic cylinder 43 having an external covering of rubber or the like material 44. Heads 45 and 46 are provided in the ends of the cylinder for the purpose of making it a liquid-tight container and to provide supports for the shaft 42. The shaft 42 is journaled in the bearings 47 and 48 and, as previously described, is driven by the pulley 41 and the belt 39. A removable plug 49 is provided in the head 46 for the introduction of a weighting material 51 such as water, oil or other liquid or granular substance within the ironer. The amount of said weighting material may, of course, be readily determined by experiment taking into consideration the size of the ironer and the average condition of the sand passing under the ironer.

Attention is again directed to Figs. 4 and 5. The sand, after receiving the treatment afforded by the ironer 5, either falls from the temper-

ing belt 3 or else is scraped therefrom by the scraper 52. The scraper 52 is preferably supported by the extensions 53 secured to the general framework 13 and comprises a toggle construction mounted upon the journaled shaft 54 which extends through the bearings 55 and 56. A weighted lever 57 secured to one end of the shaft 54 is provided to maintain the scraper blade 58 normally against the tempering belt to remove any particles or wads of sand adhering to the belt. Satisfactory material for use as a scraper blade 58 is hardwood; however, if desired, other materials may be used.

As more clearly shown in Figs. 1, 2 and 3, the sand after leaving the tempering belt 3 drops into a conventional mixer or beater 6, as previously explained, and, as it is advanced toward the outlet 7 thereof, receives a thorough mixing, beating and fluffing treatment which suitably prepares the sand for use by a foundryman in making molds. The mixer 6 is preferably provided with a belt drive 59. From the mixer outlet 7 the sand needs only to be transported to the location of its use and in the event that it must be taken some distance from the mixer, a satisfactory method of transporting and incidentally cooling the sand is provided by the belt conveyor 8 traveling around the roller 61 mounted upon the bearings 62 and the framework 63.

Having thus described and illustrated a preferred embodiment of my mulling apparatus, I wish it to be clearly understood that various changes and modifications of the construction may be made without departing from the spirit and scope of the invention as defined by the claims appended hereto.

I claim:

1. A continuously operating type sand muller comprising screening means, a sand tempering and transporting belt encircling a pair of journaled rollers, an ironer, the said ironer comprising a rotatable roller, the said belt being horizontal and flexible or freely suspended in the region of the journaled roller adjacent the said ironer, a flexibly mounted carrying member for the said rotatable roller positioned adjacent one of the journaled rollers of the said transporting belt, the said rotatable roller being mounted in spaced relation above an end flexible portion of the horizontal plane surface portion of the said belt, the axis of the said rotatable roller being offset from the vertical plane of the said journaled roller axis in a direction toward the portion of the belt between said journaled rollers.

2. A continuously operating type sand muller comprising a riddle, a tempering conveyor belt operating at a predetermined velocity upon a pair of pulleys, an ironer comprising an independently driven weighted roller mounted upon a pivotable carrying member in proximity to an end portion of the said conveyor and adjacent to one of the said pulleys, the said weighted roller being axially disposed from the said pulleys in a direction toward the span of the said belt as defined by the space between the said pair of pulleys, whereby upon the conveyance of sand upon the said belt, the span of the latter member is compressible over a section beneath and adjacent to the said weighted roller, the said belt being horizontal and flexibly or freely suspended in the region of the journaled roller adjacent the said ironer, the said roller having a peripheral velocity which is not the same as the velocity of the said tempering conveyor belt.

WILLIAM BAXTER.
